THREE DIMENSIONAL GAME BOARD

Bill Markham, Los Angeles, Calif., assignor to Lakeside Industries, Inc., Minneapolis, Minn., a corporation of Delaware

Filed Sept. 18, 1962, Ser. No. 71,748

Term of patent 14 years

(Cl. D34—5)

FIG. 1

FIG. 2

FIG. 3

FIG. 1 is a top plan view of a three dimensional game board embodying my new design;

FIG. 2 is a side elevational view thereof taken as on line 2—2 in FIG. 1; and

FIG. 3 is an enlarged front perspective view of a tower portion thereof. The sides not shown have substantially the same appearance as the side shown, the bottom being substantially plain.

I claim:

The ornamental design for a three dimensional game board, as shown and described.
